(57) **CLAIM**

The ornamental design for a scooter transport container, as shown and described.

DESCRIPTION

FIG. 1 is a top front perspective view of the scooter transport container showing my new design;
FIG. 2 is a top rear perspective view thereof;
FIG. 3 is a front elevation view thereof;
FIG. 4 is a rear elevation view thereof;
FIG. 5 is a right elevation view thereof;
FIG. 6 is a left elevation view thereof;
FIG. 7 is a top plan view thereof;
FIG. 8 is a bottom plan view thereof;
FIG. 9 is a section view thereof, taken along line 9-9 in FIG. 5, with a scooter in place;
FIG. 10 is a section view thereof, taken along line 10-10 in FIG. 5, with a scooter in place; and,
FIG. 11 is a top plan view thereof, with the top panel exploded to show the interior.
The broken lines shown in the drawings illustrate environment that forms no part of the claimed design.
